(57) **CLAIM**

The ornamental design for a vial grabber, as shown and described.

DESCRIPTION

FIG. 1 is a front, top perspective view of a vial grabber in a state of use;

FIG. 2 is a front, top perspective view thereof with vials removed;

FIG. 3 is a top plan view thereof;

FIG. 4 is a bottom plan view of thereof;

FIG. 5 is a front elevation view thereof;

FIG. 6 is a back elevation view thereof;

FIG. 7 is a left elevation view thereof; and,

FIG. 8 is a right elevation view thereof.

The short dash broken lines in the drawings depict portions of the vial grabber that form no part of the claimed design. The long dash lines depict environmental subject matter only and form no part of the claimed design.
